UNITED STATES PATENT OFFICE.

JOHN W. RAPP, OF FLUSHING, NEW YORK.

CAR-BODY.

1,114,804.

Specification of Letters Patent. Patented Oct. 27, 1914.

Application filed November 25, 1912. Serial No. 733,234.

To all whom it may concern:

Be it known that I, JOHN W. RAPP, a citizen of the United States, and a resident of Flushing, in the county of Queens and State of New York, have invented certain new and useful Improvements in Car-Bodies, of which the following is a specification.

This invention relates to improvements in metal car bodies.

- 10 The main object of my invention is to produce an all metal car body which will be strong, durable and of pleasing outward appearance and design at a minimum cost of manufacture and the principal parts of 15 which will be capable of being quickly assembled and keyed together without the use of rivets, screws, bolts or the like which mar or disfigure the outward appearance of the car body, the outer sheathing being keyed 20 to the inner frame or posts and all the usual vertical rows of rivets, screws and bolts being eliminated by such keying connection; furthermore all the necessary rivets for connecting the posts, sheathing and side sills of 25 the truck are placed in horizontal alinement and covered and concealed by a suitable molding having itself a concealed fastening. Furthermore I have produced a novel hollow vertical post having great rigidity and 30 embodying window and shade grooves, which is, first, capable of ready and secure connection to the outer sheathing by keying strips welded to such sheathing, thus, as aforesaid materially diminishing the number 35 of disfiguring or marring rivets necessary in the building of car bodies and assisting in the more ready assembling of parts, and, second, its parts are capable of being readily rolled into shape.
- 40 In the preferred embodiment of my invention, the frame of the car body embodies, first, corner posts, each comprising a hollow box-like body-portion and a post cover, the body-portion, which is formed from a single 45 strip of sheet metal bent so as to form integral window and shade grooves, and laterally-extending marginal flanges, is connected to the truck at its lower end, and the post cover, which is also formed of a single 50 strip of sheet metal so bent as to form in-turned marginal flanges providing locking grooves at each edge and adapted to interlock with the flanges of the body portion, has two flat welding surfaces at right angles 55 to each other which are welded to adjacent corner plates of the outer sheathing, and

second, a series of intermediate posts also connected at their lower ends to the cross ties of the car truck, each of such intermediate posts comprising a body-portion and a 60 post cover, the body-portion being hollow, formed of two rolled-up pieces keyed together, and having shade and window-sash grooves, one of the two pieces of the body-portion being bent to form an integral 65 window-sash groove, and the shade-groove being formed between the adjacent surfaces of the pieces. The body-portion of each intermediate post is also provided with laterally extending marginal flanges, and the 70 intermediate post covers are each formed from a single strip of sheet metal so formed as to provide a central flat welding surface which is welded to the inner surface of the outer sheathing and inturned marginal 75 flanges forming locking grooves at each edge and adapted to interlock with the flanges on the body-portion. Thus a series of the body-portions of the posts are suitably connected by rivets or otherwise to the truck 80 and a series of the post covers are welded to the inner surface of the sheathing so that the inturned interlocking flanges of the post covers will register and interlock with the lateral marginal flanges of the body-portion 85 of the post. The sheathing plates, carrying such post covers or vertical keying strips are slid downwardly over the outwardly-projecting marginal flanges of the posts, such post flanges being inserted in the locking 90 grooves of the keying-strip, thus securely locking the post and sheathing together and closing the open outer edge of the post. The sheathing is preferably slid down over the side sill of the car and these 95 parts are then preferably riveted together by a row of horizontally-aligned rivets, the exposed ends of which are subsequently covered and concealed by horizontal molding keyed to the sheathing and having a concealed fastening; a belt rail is also connected to the outer surface of top edge of the sheathing by a row of horizontally-aligned rivets, the exposed ends of which rivets are likewise covered and concealed by a horizontal 100 molding keyed to the belt rail and having a concealed fastening. The upper or window portions of the posts may be covered or faced with post covers or keying-strips forming an integral part or continuation of 105 the cover welded to the sheathing, suitable cut-outs being made for the belt-rail, or

separate strips may be locked to the flanges of the posts at such places. Carlines or roof braces are then secured to the upper ends of the posts and the roof plates or sheathing is secured in any suitable manner to complete the car-body.

In the accompanying drawings, in which similar reference characters designate corresponding parts throughout the several views, Figure 1 is a side elevation of a car embodying my invention; Fig. 2 is a section on the line 2—2 of Fig. 1; Fig. 3 is a diagrammatic plan of the front portion of the car, the roof having been removed; Fig. 4 is a section on the line 4—4 of Fig. 1; Fig. 5 is a perspective view of a section of an intermediate side post; Fig. 6 is a perspective view of a corner post; Fig. 7 is a section on the line 7—7 of Fig. 4; Fig. 8 is a section on the line 8—8 of Fig. 4; and Fig. 9 is a detail of the connection between the outer sheathing, belt rail and the rivet-concealing molding of such belt rail. Fig. 10 is a detail of the rivet connection of the sheathing and side sill, the concealing molding and fastening device being omitted; Fig. 11 is a similar view of the rivet connection between the belt rail and sheathing, the concealing molding and fastening being omitted; Fig. 12 is a detail plan showing the fastening device for keying the rivet concealing side sill molding, the same being partially broken away; and Fig. 13 is a similar view of the fastening device in relation to the rivet-concealing belt-rail molding, the said molding and belt-rail being partially broken away. Fig. 14 is an enlarged detail view of the connection between the outer sheathing, side sill and transverse ties illustrated at the lower end of Fig. 4.

Referring now to these drawings, Fig. 1 illustrates a metallic car body having side sills B which comprise channel irons standing on edge with the flat web portion facing outwardly, connected to cross ties B' in any suitable manner and having the usual platform supports B². Secured to the cross ties B' of the truck B in any suitable manner so as to form upright framing members of the inner frame of the car body, and as shown connected to said truck by means of riveted angle plates C (see Fig. 4) are corner and intermediate posts D D' respectively. The posts D D' comprise body portions d d' each made up of one or more strips rolled into shape, the corner posts having integral shade and window grooves d⁴ d⁵ at one side and the intermediate posts having such grooves d⁴ d⁵ at both sides. Such body-portions d d' are, as shown, (see particularly Figs. 2, 5 and 6) hollow, open at their outer edges and provided with laterally-extending marginal flanges along the longitudinal or vertical edges thereof.

The outer sheathing, comprising the

flat plates E is secured in place in the following manner: Post covers or keying strips d² d³ for the intermediate and corner posts each have one or more central flat portions adapted to be electro-welded to the inner 70 surface of the sheathing and at opposite sides of such welding surfaces have in-turned marginal flanges so as to form locking grooves between the same and the body or central flat portion or portions thereof. A series of such strips are so electro-welded at such central portions to the sheathing plates at such places as will register with and cover the open ends of the body-portions of the posts. As illustrated, the body 80 portion of each corner post is formed of a single strip of metal and rolled to have integral shade and window grooves d⁴ d⁵ at one side and to have outwardly extending marginal flanges d⁷ d⁸ at its opposite edges, 85 which flanges extend at right angles to each other and the cover or keying strips for corner posts D are provided with two flat welding surfaces d⁹ d¹⁰ at right angles to each other and such surfaces are welded to adjacent sheathing plates also disposed at right angles to each other so as to form a corner of the car; and each post cover or keying strip has at its opposite longitudinal edges in-turned marginal flanges d¹¹ and d¹² 95 forming locking grooves for the reception of the flanges on the body portion of the post as aforesaid. The meeting edges of such corner sheathing plates are preferably covered by means of an arc-shaped or circular molding F fastened to the corner post cover or keying strip e by means of bolts f which do not, however, extend through to the outer surface of such molding strips F 100 so as to disfigure the same, but are connected to such molding by means of what I shall term distance pieces f' welded at suitable places to the inner surface of the molding F, the bolts being inserted into apertures in the distance pieces before the welding of the same to the molding. If desired, however, the heads of the bolts may be directly welded to the inner surfaces of the molding. The opposite edges of such arc-shaped molding F may be thus firmly held over the joining line of the two adjacent plates and in contact therewith so as to form an extremely neat joint at this particular point without the use of exposed screws, 105 bolts or other fastening devices.

In the preferred form of the invention shown, each of the intermediate posts D' have a body portion d' rolled to form at each side thereof an intermediate integral window groove d⁶ and opposing laterally-extending marginal flanges d¹³ d¹⁴, and the cover or keying strips d² for such post has a central welding surface welded to the sheathing E and is provided at its opposing marginal edges with in-turned marginal 110

flanges d^{15} d^{16} forming locking grooves which receive and permit interlocking with the marginal flanges d^{13} d^{14} of the body portion d' of such posts. The shade grooves d^4 of these intermediate posts are preferably formed at each side thereof by bending a separate metal strip d'' and then keying it to the rear end of the body portion of the post d' so as to leave the said groove d^4 between said body portion d' and the strip d'' . As illustrated, the said strip d'' is formed with inwardly-projecting marginal flanges d^{17} d^{18} and an L-shaped portion at both sides contiguous to such marginal flanges, which 15 L-shaped portion forms the rear and side walls of said shade groove d^4 and the other wall of said groove is formed by the outer face of the body portion d' . The marginal flanges d^{17} d^{18} interlock with a keying strip 20 d^8 suitably connected to the body portion d' , the said keying strip d^8 being as shown provided with a depressed central portion which is secured to the said body portion and marginal flanges slightly raised above the 25 surface of the body portion d' beneath which raised marginal flanges the marginal flanges of the strip d'' interlock. The cover or keying strips d^2 , d^8 being welded as aforesaid to the outer sheathing plates E, these plates 30 may now be slid downwardly with the marginal flanges of the post entering the locking grooves formed by the marginal flanges on the keying strips or post covers into position on the frame. The sheathing is thus 35 preferably slid downwardly to the lower edge of the side sills B whereupon such heating plates and side sills are rigidly riveted together by a series of horizontally aligned rivets b and these horizontally aligned rivets are 40 completely covered and concealed by a horizontal molding strip b^2 having inturned marginal flanges b^3 b^4 keying or interlocking with a series of short keying strips b' each having flat central connecting surfaces 45 which surfaces are connected to the sheathing E, and marginal flanges raised above the sheathing, such strips b^2 being similar to the keying strip d^8 above described, (see Figs. 4, 10 and 12), and thus effectually concealing 50 the horizontally aligned rivets. These keying strips b' are secured as aforesaid to the sheathing intermediate the rivets b and the inturned flanges of the molding b^2 are slid beneath and engage and interlock with such 55 keying strips b' .

A belt rail G, having a downwardly extending flange g (see Fig. 9) is secured at the upper edge of said sheathing E beneath the window sashes G', the downwardly extending flange g being riveted directly to the sheathing by a series of horizontally aligned rivets h of suitable binding strength and these horizontally aligned rivets are covered and concealed by a belt rail molding H having 60 inturned flanges and keyed or interlocked to a series of suitable short keying strips h' , each of which have central connecting surfaces, which are connected to the downwardly extending flange g , and raised marginal flanges beneath which the inturned flanges of the belt rail molding interlock, the molding flange being slid endwise beneath such raised flanges, thus effectually concealing this row of horizontal rivets. The post covers d^2 are preferably cut away at such points as is necessary to permit the connection of the belt rail or if desired a portion of the belt rail may be notched to permit the post covers to extend the entire length of the post. The carlines are then connected to the post and the roof sheathing E' is set in place on these carlines and connected in any suitable manner. The platform posts are preferably of a different configuration than either the intermediate or connected to the post and the roof sheathing and posts are connected in a similar manner.

Having described my invention, I claim:

1. A car body embodying therein an outside sheathing, post members having body portions that form part of the interior frame, a post-cover connected to the car sheathing, and means for interlocking the body-portion and cover to attach the sheathing to the interior frame.
2. A car body embodying therein an outside sheathing, post members having body portions that form part of the interior frame, a post-cover welded to the inner surface of the car sheathing and interlocking flanges on said body-portion and post-cover for keying the post parts together to secure the sheathing to the frame.
3. A car body embodying therein an outside sheathing, post members having a body portion formed of sheet metal bent intermediate its longitudinal edges to provide a hollow post and spaced marginal flanges, and a post-cover also formed of sheet metal bent to provide marginal flanges adapted to interlock with the flanges of the body portion, said post-cover having the double function of reinforcing the post and securing the sheathing thereto without exposed rivets.
4. A car body embodying a sheathing and post members, each composed of two parts, one part having outwardly projecting flanges, the other part having inwardly extending flanges adapted to interlock with the outwardly extending flanges of the first mentioned part and one of such parts having a welded connection to the inner surface of the outside sheathing.
5. A car body embodying suitable side sills, an outside sheathing, post members having a welded connection with the inner surface of said sheathing, a row of horizontally aligned rivets connecting the side sill and sheathing and a rivet concealing hori-

zontal molding attached to the sheathing over said horizontally alined rivets.

6. A car body embodying suitable side sills, an outside sheathing, post members having a welded connection with the inner surface of said sheathing, a row of horizontally alined rivets connecting the side sill and sheathing, a rivet concealing horizontal molding attached to the sheathing over said 10 horizontally alined rivets, a metallic belt rail, a row of horizontally alined rivets con-

necting the belt rail and sheathing and a horizontal molding having concealed fastenings for concealing such belt rail rivets.

In witness whereof, I have signed my 15 name to the foregoing specification in the presence of two subscribing witnesses.

JOHN W. RAPP.

Copies of this patent may be obtained for five cents each, by addressing the "Commissioner of Patents, Washington, D. C."

It is hereby certified that in Letters Patent No. 1,114,804, granted October 27, 1914, upon the application of John W. Rapp, of Flushing, New York, for an improvement in "Car-Bodies," an error appears in the printed specification requiring correction as follows: Page 3, strike out line 86, and insert the words and syllable *corner posts but in other respects the sheath-*; and that the said Letters Patent should be read with this correction therein that the same may conform to the record of the case in the Patent Office.

Signed and sealed this 23rd day of March, A. D., 1915.

[SEAL]

J. T. NEWTON,

Acting Commissioner of Patents.
